C. E. SCHULZ,
RADIATOR REPAIR MACHINE,
APPLICATION FILED JAN. 2, 1920.

1,405,340.

Patented Jan. 31, 1922.

UNITED STATES PATENT OFFICE.

CLYDE E. SCHULZ, OF FORT DODGE, IOWA.

RADIATOR-REPAIR MACHINE.

1,405,340.

Specification of Letters Patent. Patented Jan. 31, 1922.

Application filed January 2, 1920. Serial No. 349,081.

To all whom it may concern:

Be it known that I, CLYDE E. SCHULZ, a citizen of the United States, and resident of Fort Dodge, in the county of Webster and 5 State of Iowa, have invented a certain new and useful Radiator-Repair Machine, of which the following is a specification.

The object of my invention is to provide a radiator repair machine of simple, durable 10 and inexpensive construction, adapted particularly for use in repair shops for the speedy and convenient handling and repair of radiators.

More particularly it is my object to provide a radiator repair machine including a frame and burner mechanism, with the parts so arranged as to facilitate the handling and heating of a portion of the radiator for removing, for instance, the bottom pan 20 thereof, for repairing the tubes or fins, and for completing the repair by putting on the pan.

With these and other objects in view, my invention consists in the construction, arrangement and combination of the various parts of the device, whereby the objects contemplated are attained, as hereinafter more fully set forth, pointed out in my claims, and illustrated in the accompanying drawings, in which:

Figure 1 shows an end elevation of a radiator repair machine embodying my invention.

Figure 2 is a top or plan view of the same.

Figure 3 is a detail sectional view, taken on the line 3—3 of Figure 2.

Figure 4 is an enlarged detail view of the crank and ratchet and rack mechanism for 40 raising and lowering the burners; and

Figure 5 shows a detail, transverse, sectional view, similar to Figure 3 but illustrating a modification.

In the drawings herewith, whereby my invention is illustrated, I have shown a frame, which frame consists of four corner posts indicated by the reference character 10. The respective corner posts at each end of the machine are inclined toward each other somewhat, as indicated in Figures 1 and 3. The corner posts 10 on each side of the machine are connected at their ends by longitudinal side frame members 11. The posts 10 at the ends of the machine are connected 50 by transverse frame members 12 located sub-

stantially below the upper end of the frame, as illustrated in Figure 1.

It will thus be seen that I have provided a frame which is formed at its upper portion with longitudinal side members and with 60 transverse end members which are lower than the side members, so that a free space is provided above the transverse end members and between the sides of the frame at the upper end thereof.

Suitable brace members 13 and 14 are provided at the sides and ends of the machine.

At each end of the machine I preferably provide a bracket 15, having vertically spaced bearings 16 for a vertically 70 65 slideable rod or shaft 17. Each shaft 17 supports at its upper end a transverse member 18.

Supported on the transverse members 18 is a plurality of laterally spaced, longitudinally arranged burner tubes 19. Mounted on brackets 20 and 21 at one side of the machine, is a supply pipe 22, which at its upper end communicates with a sort of manifold 23. The manifold 23 is connected by flexible conducting pipes 24 with the respective burner tubes 19.

On each rod 17, between the bearings 16 in which said rod is mounted, is a rack bar 25. Suitably mounted on the machine, as, for instance, in bearings 26 on the brackets 15, is a longitudinally arranged shaft 27 having on one end the crank 28. Mounted on the shaft 27 are pinions 29 which mesh with the respective rack bars 25. Pivoted to one of the brackets 15 is a pawl 30, adapted to coact with the gear 29 for locking the gears 29 in various positions of their movement, for thereby holding the rods 17 in any of their raised positions.

It will be seen that by suitable manipulation of the crank 28, the gears 29 may be rotated for coacting with the racks 25 for raising or lowering the rods 17 and thereby raising or lowering the burner tubes 19, as may be desired.

Extending laterally from one side of the upper end of the main frame is a supporting platform 31, having substantially the form of a grid, as illustrated in Figure 2. This platform may be supported partially 105 by braces 32, if desired. Supported at one end of the machine is an upright 33, which projects upwardly above the frame. Pivotally mounted on the upright 33 is a pan 34 of proper size to permit the dipping of the 110

end of a radiator therein. The pan 34 is mounted so that it may be swung to and from position above the burner tubes 19 and above the frame generally.

5 Supported on the end members 12 by means of short fingers or hooks 35, is a dripping pan 36 which may be readily lifted up and removed when desired.

It may be mentioned that the burner tubes 19 are heavy enough so that they may be allowed to rest of their own weight on the cross members 18. They can then be readily moved to different positions for applying the heat in the desired places.

15 In Figure 5 I have shown a slightly modified form of my invention.

In the form shown in Figure 5, the parts are as hereinbefore described, except that instead of the upright 33 there is provided an upright 60 fixed in position at one side and at one end of the main frame. Supported at the upper end of the upright 60 is a solder pan 61 extending along side of and above the main frame, as illustrated in said figure.

25 Supported on the frame 10 are laterally supporting brackets 62 on which are mounted suitable burner tubes 63 which may be connected with any source of fuel supply.

30 In the form of the invention shown in Figure 5, the contents of the pan or container 61 may be heated slightly while the radiator is being heated from the burner tubes 19.

35 In the practical use of my improved machine, and assuming that it is desired to repair the lower portion of an ordinary radiator having fins and water-conducting tubes, it may be understood that the radiator may be laid on the platform 31 with its lower portion projecting over the burner tubes 19. The burner tubes are lighted, and by moving the radiator in one direction, as much or as little of the lower part of the radiator may be subjected to the heat from the burners as may be desired. By operating the crank 28 and parts connected therewith, the burners may be raised and held in any desired position. It will be seen that the bottom pan or portion of the radiator may be removed by melting the solder, and thereafter the fins or tubes may be repaired.

40 During the repairing process, solder may be heated in the pan 34 by raising the burners 19 as high as possible and keeping the pan 34 directly above the burners, so that when the fins or tubes have been repaired the lower portion of the radiator may be simply dipped in the hot solder in the pan 34, for completing the soldering operation.

45 It will be seen that I have provided a repair machine which is of simple and inexpensive construction, and which greatly adds to the facility and convenience of repairing radiators.

Some changes may be made in the construction and arrangement of the various parts of the machine without departing from the real purpose and spirit of my invention, and it is my intention to cover by my claims 70 any modified form of structure or use of mechanical equivalents that may be reasonably included within their scope.

I claim as my invention—

1. In a radiator repair machine, a supporting frame comprising side members, end members arranged below the upper end of said frame, a burner device mounted for vertical reciprocation between said side members and above the level of said end members, a laterally extending frame at the upper part of said first frame, for supporting a radiator with a portion thereof projecting over said burner device, and a movable receptacle mounted for movement 80 to and from position above said burner device.

2. In a radiator repair machine, a supporting frame comprising side members, end members arranged below the upper end of 90 said frame, a burner device mounted for vertical reciprocation between said side members and above the level of said end members, a laterally extending frame at the upper part of said first frame, for supporting a radiator with a portion thereof 95 projecting over said burner device, a movable receptacle mounted for movement to and from position above said burner device, and a drip receptacle arranged below 100 said burner device.

3. In a radiator repair machine, a supporting frame comprising side members, end members arranged below the upper end of said frame, a burner device mounted for 105 vertical reciprocation between said side members and above the level of said end members, and a laterally extending frame at the upper part of said first frame, for supporting a radiator with a portion thereof 110 projecting over said burner device, said burner device including a plurality of laterally spaced, longitudinally arranged burner tubes, the parts being so arranged that by moving a radiator on said platform, the 115 projecting portion of said radiator may be subjected to strong heat from one or more of the burner tubes, as may be desired.

4. In a radiator repair machine, a supporting frame comprising side members, end 120 members arranged below the upper end of said frame, a burner device mounted for vertical reciprocation between said side members and above the level of said end members, a laterally extending frame at 125 the upper part of said first frame, for supporting a radiator with a portion thereof projecting over said burner device, said burner device including a plurality of laterally spaced, longitudinally arranged burner 130

tubes the parts being so arranged that by moving a radiator on said platform, the projecting portion of said radiator may be subjected to strong heat from one or more of 5 the burner tubes, as may be desired, a supply tube, a manifold connected therewith, and flexible tubes connecting said manifold with the respective burner tubes.

5. In a radiator repair machine, a supporting frame comprising side members, end members arranged below the upper end of said frame, a burner device mounted for vertical reciprocation between said side members and above the level of said end members, 10 a laterally extending frame at the upper part of said first frame, for supporting a radiator with a portion thereof projecting over said burner device, said burner device comprising transverse end members, longitudinally arranged, laterally spaced burner tubes supported on said end members, 15 upright rods, slidably mounted, supporting said end members, means for supplying fuel to said burner tubes, and means for raising or lowering said upright rods and for hold-

20

25

ing them in their various adjusted positions.

6. In a radiator repair machine, a supporting frame comprising side members, end members arranged below the upper end of said frame, a burner device mounted for vertical reciprocation between said side members and above the level of said end members, a laterally extending frame at the upper part of said first frame, for supporting a radiator with a portion thereof projecting over said burner device, said burner device comprising transverse end members, longitudinally arranged, laterally spaced burner tubes supported on said end members, 30 upright rods, slidably mounted, supporting said end members, means for supplying fuel to said burner tubes, and means for raising or lowering said upright rods and for holding them in their various adjusted positions, 35 said means including racks on said upright rods, a shaft, gears thereon in mesh with said racks, and means for rotating said shaft.

Des Moines, Iowa, October 31, 1919.

CLYDE E. SCHULZ.
